UNITED STATES PATENT OFFICE

JOHN P. DESMET, OF MODESTO, CALIFORNIA, ASSIGNOR TO E. R. HAWKE, OF MODESTO, CALIFORNIA

AIRPLANE SPRAY DEVICE

Application filed September 29, 1931. Serial No. 585,720.

This invention relates to devices for spraying for the control of insect and other pests on vegetation, as well as noxious weeds etc., with the aid of an airplane.

5 The principal object of my invention is to provide a device for the purpose, mounted on the airplane and so arranged that the spray liquid will be automatically atomized by reason of the rush of air induced by the flight of 10 the airplane, and distributed on the vegetation or ground in the form of streams along the line of flight. This is accomplished without the aid of any power operated mechanism on the airplane.

15 A further object of the invention is to produce a simple and inexpensive device and yet one which will be exceedingly effective for the purpose for which it is designed.

These objects I accomplish by means of 20 such structure and relative arrangement of parts as will fully appear by a perusal of the following specification and claims.

In the drawing similar characters of reference indicate corresponding parts in the several views:

Fig. 1 is a fragmentary perspective outline of an airplane showing my improved spray device mounted thereon.

Fig. 2 is a front view of one of the spray units detached.

Fig. 3 is a side elevation of the same partly in section.

Fig. 4 is an enlarged fragmentary section of the unit and its supporting shaft.

35 Referring now more particularly to the characters of reference on the drawing, the numeral 1 denotes a shaft adapted to be mounted in a fixed position on an airplane so as to extend lengthwise thereof and to one 40 side of and outside the fuselage. This shaft for instance is preferably mounted in connection with one of the struts 2 of the landing wheels 3 of the airplane as indicated in Fig. 1.

45 Turnably mounted on the forward end of the shaft is a propeller having two or more blades 4 which are preferably of rectangular form and set at a suitable pitch. Owing to the position in which the shaft is mounted the propeller is of course exposed to the horizontal air current set up with the flight of the

airplane and the propeller will be rotated without any connection with the engine of the airplane being necessary.

Formed in the blades at their outer ends are Venturi tubes 5 whose axes are disposed in planes parallel to the shaft and which extend from the leading to the following edges of the blades; a series of these tubes being employed if an increase in the capacity of the device is desired. Liquid passages 6 are formed in the blades and extend from the hub of the propeller to the tubes at their throat. The liquid is fed to the passages from a passage 7 bored through the shaft from its rear end and delivering to a circumferential groove 8 cut in the shaft in alinement with the adjacent ends of the passages 6, so that the latter will constantly receive liquid with the rotation of the propeller on its shaft. The liquid is supplied to the shaft passage from a pipe 9 connected to the rear end of the shaft; a supply of liquid sufficient for continued operation for a certain time without replacement being carried in the fuselage of the airplane and suitably connected to the pipe 9. I preferably employ two of the propeller units which are mounted on opposite sides of the airplane in symmetrical relation to each other.

In operation with the flight of the airplane 80 a constant stream of relatively moving air induced by the movement of the airplane is directed horizontally against the forwardly facing propellers causing their rotation. With this rotation the liquid is thrown centrifugally through the passage 6 into the Venturi tubes at the outer ends of the blades. With the turning of the leading edges of the blades into the air a flow of air at high velocity is set up through these tubes, causing the liquid as discharging therein to be atomized and mixed with the air passing through the tubes. The mixture is then forcefully discharged from the ends of the tubes at the following edges of the blades and is thrown 90 transversely of the airplane.

95 Due to the horizontal air currents to which the mixture is subjected as soon as it leaves the propeller however it will not travel transversely to any distance but will be deflected 100

rearwardly, so that when the airplane is in flight the discharges from the propellers will have the appearance of continuous rearwardly moving streams.

8 From the foregoing description it will be readily seen that I have produced such a device as substantially fulfills the objects of the invention as set forth herein.

10 While this specification sets forth in detail the present and preferred construction of the device, still in practice such deviations from such detail may be resorted to as do not form a departure from the spirit of the invention, as defined by the appended claims.

15 Having thus described my invention what I claim as new and useful and desire to secure by Letters Patent is:

1. In combination with an airplane, a propeller mounted thereon in position to be rotated by the air stream induced by the flight of the airplane, Venturi tubes in the blades of the propeller extending from the leading to the following edges thereof, and means to supply liquid to the Venturi tubes.

20 2. In combination with an airplane, a propeller mounted thereon in position to be rotated by the air stream induced by the flight of the airplane, Venturi tubes in the blades of the propeller extending from the leading to the following edges thereof, a shaft on which said propeller is mounted, and continuous liquid passage means leading through the shaft and blades to the Venturi tubes.

25 3. In combination with an airplane, a propeller mounted thereon in position to be rotated by the air stream induced by the flight of the airplane, Venturi tubes in the blades of the propeller extending from the leading to the following edges thereof, and means to supply liquid to the throats of the Venturi tubes from within the propeller.

In testimony whereof I affix my signature.
JOHN P. DESMET.
